(57) **CLAIM**

I claim the ornamental design for a display screen with a list generation graphical user interface, as shown and described.

DESCRIPTION

FIG. 1 is a front view of a display screen with a list generation graphical user interface of the present invention. FIG. 2 is a front view of the display screen with another list generation graphical user interface; and, FIG. 3 is a front view of the display screen with another list generation graphical user interface.

The outermost broken line illustrates the display screen and forms no part of the claimed design. The remaining broken lines illustrate portions the list generation graphical user interface and form no part of the claimed design.

1 Claim, 3 Drawing Sheets
